METHOD OF MAKING PRINTING ROLLERS

Samuel F. Damm, Niagara Falls, N. Y.

Application March 20, 1935, Serial No. 11,990

3 Claims. (Cl. 101—401.1)

My invention relates in general to a method of making printing rollers and more particularly to such a method as applied to the manufacture of wall paper printing rollers.

It is well known to those skilled in the art that it has been proposed to use metal for wall paper printing rollers in the surface of which are routed the various designs of the roller. Such rollers are not only heavy to handle but they are costly because of the labor required in routing out the portions of the rollers between the designs so as to get the proper clearance.

The principal object of my invention has been to provide a method whereby rollers may be inexpensively and economically made. To this end my invention contemplates the use of relatively soft material in the form of a cylinder, the surface of which has a radius substantially the same as the printing radius of the finished roller from which the individual printing designs are cut in most economical manner. These individual designs are then afterwards set into a roller having a corrugated exterior surface to which they are secured by suitable means.

In the accompanying drawing I have shown, as an illustration of my method, a roller made up in accordance therewith.

Obviously, while I show in the drawing the material from which the designs are cut in the form of a hollow sleeve, it is evident that the material may be in the form of a curved sheet or that it may be flat and the designs bent in the form of a curve after having been finished and cut therefrom.

In the drawing:

Fig. 1 is a perspective view of the supply roller or sheet of material from which the individual designs are cut, showing some of the designs routed out and others marked ready for routing.

Fig. 2 is a perspective view of one of the finished individual designs.

Fig. 3 is a fragmentary, side elevation of one end of the roller showing one step in my process.

Fig. 4 is a fragmentary view of another portion of the same roller showing the finished product.

Fig. 5 is an end sectional elevation taken on line 5—5 of Fig. 3 and shows in elevation the completed portion of the roller shown in Fig. 4.

Fig. 6 is a fragmentary, plan view showing another step in the process.

Fig. 7 is a perspective view of a modified form of individual design.

Fig. 8 is a transverse, sectional view of a roller showing the design of Fig. 7 secured in place.

Fig. 9 is a longitudinal, sectional elevation of the form of invention shown in Fig. 8.

Reference is now to be had to the drawing and particularly to the form of invention shown in Figs. 1 to 6 inclusive. In carrying out my invention, I provide the material from which to cut the individual design preferably in the form of a supply cylinder 15 on the periphery of which I arrange the series of individual designs 16 in the most economical way and in such manner that there shall be the least possible waste of material, as shown in Fig. 1. The outer diameter of the supply cylinder is preferably the same as the diameter of the printing surface of the roller. The outlines of these designs are marked 15 on the supply cylinder as they are arranged, after which the cylinder is placed in a suitable routing machine (not shown) and the design routed out, as shown on part of the cylinder in Fig. 1. Extending from the printing surface 17 of each individual design is a flange 18. The flanges 18, as shown in broken lines in Fig. 1, are formed as the printing surfaces 17 are being routed out and the upper surface of each, therefore, lies considerably below the printing surface 17 so as 20 to provide sufficient clearance. The flange 18 is left sufficiently thick so as to be rigid enough to provide means for securing the design in place, to be later described. After the printing surface 17 is provided and the flange is routed to the desired thickness, the designs are severed from the sheet material by being cut around the flanges 18. Obviously this may be done either by routing through the material with the routing tool or may be severed by any other suitable means. 30 Each of the individual designs, when finished, assumes a form similar to that shown in Fig. 2.

The next step in carrying out my invention is the provision of a printing roller 20 shown in fragmentary manner in Figs. 3, 4, and 5. The body 21 of this roller is preferably made of sheet metal relatively thin and suitably reinforced on the inside by means of corrugated sleeves 22 and 23. Heads 24 (only one of which is shown) are each provided with a suitable central opening 25 for the reception of the usual driving shaft 27 and/or conical centering bushing (not shown) customary in printing rollers of this kind. Around the outside of this roller body 21 is placed an outer corrugated sleeve 26, the height of which is preferably not great enough to extend up to the level of the printing surface of the roller which is coincident with the surface 17 of the individual design when it is in position.

The outer corrugated surface of the drum is 55

now preferably coated with some material upon which marks may be made, as for instance, white paint.

Upon this outer painted surface of the drum I now arrange the designs and I mark on the upper crests of the corrugations the contour of the design, as shown by the marks 30 in Fig. 3. Where the design of any particular roller is to be registered with a design on another roller, as in multiple color work it is, of course, quite necessary that the two designs come in registering positions. This may be done by careful laying out of the designs on the drum, or a drawing may be prepared upon which the designs are shown. This drawing may then be laid upon the corrugated outer surface of the sleeve and the outline of the design marked by using some suitable transfer material as, for instance, carbon paper. Even though the outer diameter of the corrugated sleeve is somewhat less than the diameter of the printing surface of the roller, if the designs are laid out symmetrically upon the drawing and the drawing is used on the outside diameter of the corrugations, the printing designs when in place will also be symmetrically arranged. It is, of course, obvious that the outline marking for the designs is governed by the flange 18 and not by the pattern of the design itself.

After the designs have been marked upon the outer corrugated surface of the drum, as just above described, the drum is placed in a suitable routing machine (not shown) and the tops of the corrugations over the surface bounded by the marks or lines 30 are routed out to a depth that will bring the printing surface 17 in registration with the printing diameter of the roller (as shown in Fig. 6). The thickness of the supply material is preferably such, in relation to the height of the corrugations and the diameter of the roller body 21, that the flange 18 will be let into the corrugations, as shown in Fig. 6, sufficient to provide a number of retaining detents or walls 31.

After the corrugations have been routed out, as above described, the individual printing designs, as shown in Fig. 2, are set into the recesses and are secured therein preferably by means of soldering or welding. After the printing designs are secured in place, the outer corrugated sleeve 26 is routed away leaving a relatively narrow flange 32 all around the flange 18 of the printing design. During the course of routing, this flange 32 is secured to the body 21 of the roller by means of soldering or otherwise so that its position will not be shifted during the routing-out process. After it is entirely routed out it is firmly secured in place in any suitable manner. The portions of the corrugated shell 26 lying between designs may then be quickly and conveniently removed from the roller body, as shown in Fig. 4.

When the printing surface 17 of the design is relatively large or when it is desired to use felt as a portion of such surface, the design is formed with a central opening 35 cut preferably through the material by routing, as shown in Fig. 7. A narrow band of printing surface 36 is left all around the opening 35 and between it and the outer boundary of the printing surface. A flange 18 is also provided in this form as in the form of Fig. 2. These routed-out designs, like those of the form of Fig. 2, may be prepared from supply material which is in the form of the roller 15 and they may be fitted into recesses formed in

the corrugated outer surface of the roller in a manner like the design shown in Fig. 2, above described. The felt insert 37, shown in Figs. 8 and 9, is cut to fit the inner opening 35 of the printing design. The printing design may be put in place within the recess formed in the corrugations and secured thereto, if desired, before the felt is put into the opening 35. In this manner of assembling, cement 39 is placed in the bottom of the corrugations and through the openings 38 formed by cutting off the tops of the corrugations. This cement will thus flow into the openings and spread out underneath the flanges 18 of the printing design, as shown in Fig. 9 and thereby be anchored in place. When the felt insert 37 is now placed in the opening 35 and pressed down into place, it will adhere to the cement 39, thus securing the same in position.

From the foregoing it will be clear that printing rollers made in accordance with my method are light, strong, and durable. My method, furthermore, is of such a nature that when a new design or pattern is to be created, it is not necessary to make an entirely new roller. It is only necessary to remove the portions of the outer corrugated sleeve to which the old printing designs are immediately secured and supply the body 21 of the roller with a new outer corrugated sleeve corresponding to the original corrugated sleeve 26 and to treat the new sleeve in the same manner as above described for producing a roller having the new design.

While I have shown in the drawing a specific type of supply roller and a specific form of design pattern, it is obvious that the supply roller may be in any other desired form, either a curved sheet or a flat sheet which is bent to form after being cut from the sheet. The design, of course, may be varied as desired.

Having thus described my invention, what I claim is:

1. A method of making printing rollers, comprising cutting individual designs from a supply sheet, preparing a roller having an outer corrugated sleeve, marking upon the corrugations the contour of the individual designs, routing the corrugations to the depth required to bring the printing surface of the design pattern coincident with the printing circumference of the roller, and placing and securing the designs in the recesses.

2. A method of making printing rollers, comprising cutting individual designs from a supply sheet, preparing a roller having an outer corrugated sleeve, marking upon the corrugations the contour of the individual designs, routing the corrugations to the depth required to bring the printing surface of the designs coincident with the printing circumference of the roller, placing and securing the designs in the recesses, routing around the designs leaving a portion of the corrugated shell surrounding the designs, and then removing the portions of the corrugated sleeve lying between the designs.

3. A method of making printing rollers, comprising cutting individual designs from a cylindrical supply sheet having a radius substantially the same as the radius of the printing surface of the roller, preparing a roller having an outer, longitudinally corrugated, sheet metal sleeve, and permanently securing such designs to the corrugated sleeve.

SAMUEL F. DAMM.
